US00D582421S

(12) **United States Design Patent**
Okamoto et al.

(10) **Patent No.:** US D582,421 S
(45) **Date of Patent:** ** Dec. 9, 2008

(54) **RADIO FREQUENCY IDENTIFICATION TAG READER**

(75) Inventors: **Tomoyuki Okamoto**, Kasugai (JP); **Takuya Nagai**, Nagoya (JP); **Kazuo Ito**, Aichi-gun (JP); **Hiroaki Fujino**, Nagoya (JP); **Daisuke Nakayama**, Nagoya (JP)

(73) Assignee: **Brother Industries, Ltd.**, Nagoya (JP)

(**) Term: **14 Years**

(21) Appl. No.: **29/300,140**

(22) Filed: **Feb. 26, 2008**

(30) **Foreign Application Priority Data**

Aug. 31, 2007 (JP) D2007-023672

(51) **LOC (8) Cl.** **14-02**

(52) **U.S. Cl.** **D14/453**

(57) **CLAIM**

The ornamental design for a radio frequency identification tag reader, as shown and described.

DESCRIPTION

FIG. 1 is a perspective view of a radio frequency identification tag reader;

FIG. 2 is a top view thereof;

FIG. 3 is a front view thereof; and,

FIG. 4 is a cross-sectional view taken along the line 4—4 of FIG. 2.

The broken lines depict environmental subject matter only and form no part of the claimed design.

The dot-chain lines illustrate a border of the claimed subject matter and form no part of the claimed design.
